UPSETTING MACHINE

Karl F. W. Kempf, Buffalo, N. Y., assignor to
McKaig-Hatch, Inc., Buffalo, N. Y., a corpora-
tion of New York

Application March 28, 1932, Serial No. 601,477

16 Claims. (Cl. 10—11)

My invention relates to improvements in machines for upsetting rods to form enlargements or heads thereon, or what may be termed upsetting machines.

5 The primary object of my invention is the provision of an upsetting machine for forming enlargements or heads on rods and the like and finishing the article to true and exact length without resorting to extra operations or to the
10 use of more than a single heat.

Heretofore, when forming a head or enlargement on a bar it was invariably necessary to reheat the bar after the head or enlargement was preliminarily or even rudimentarily formed, and 15 this resulted in increased costs of production and inaccuracies or variations in diameter of the head and length of the finished headed article, and considerable waste in material. Therefore, it has been found, where accuracy in the length, 20 diameter, or form of the head or enlargement and in the length of the finished headed article is desired, that the article could be produced considerably cheaper by machining the same from material to desired size; machine-headed rods, 25 screw bolts and the like being, however, considerably inferior in qualities.

A further object of my invention therefore is, to provide a headed article which shall include headed rods, bolts, or any other article formed 30 of rod material having an end enlargement or a head thereon, under a new method of manufacture; and to provide new and novel means under which such method is practiced.

A still further object of my invention is to provide 35 a heading machine which is comparatively simple in construction, and which will, under one heat of a rod or bar, form a head or end enlargement on an article of manufacture which is true in length and diameter, and also in form; and 40 also one which is true in overall length and perfect in alinement.

With these and other objects in view to appear hereinafter, my invention consists in the novel method of manufacturing headed articles and in 45 the new and novel machine for practicing such method; also in the novel features of construction, and arrangement and combination of parts to be hereinafter described and more particularly pointed out in the subjoined claims.

In the drawings:

Fig. 1 is a top plan view of a portion of a machine showing my improved invention.

Fig. 2 is a vertical section taken on line 2—2, 55 Fig. 1.

Fig. 3 is an end view of the machine shown in Fig. 1, viewed from the right.

Fig. 4 is an enlarged transverse section taken on line 4—4, Fig. 2.

Fig. 5 is an enlarged horizontal section taken on line 5—5, Fig. 2.

Fig. 6 is an enlarged vertical transverse section taken on line 6—6, Fig. 1, looking in the direction of the arrow crossing said line.

Fig. 7 is an enlarged vertical transverse section taken on line 7—7, Fig. 1.

Fig. 8 is an enlarged horizontal section taken on line 8—8, Fig. 2, the ram being shown advanced with the initial upsetting tool or forming die advanced with the ram.

Fig. 9 is an enlarged horizontal section taken on line 9—9, Fig. 2, the ram being shown advanced with the secondary upsetting tool or forming-die advanced with the ram.

Fig. 10 is an enlarged horizontal section taken on line 10—10, Fig. 2, showing the rudimentarily formed head or end enlargement on the rod in position to be finished.

Fig. 11 is a view similar to Fig. 10, showing the ram advanced and the finishing tool or die in position after completing the rudimentarily formed head to finished form.

Figs. 12 and 13 are detached perspective views of the support or carrier for the rod-supporting member, viewed from front and rear, respectively.

Figs. 14 and 15 are perspective views of the rod-supporting member, viewed from front and rear, respectively.

Fig. 16 is a detached perspective view of the rod shearing element.

Fig. 17 is a detached perspective view of the rod squaring plunger or stud.

Fig. 18 is a detached perspective view of the pivoted actuator for the rod squaring plunger or stud.

Fig. 19 is a detached perspective view of one of the rod nicking or marking devices.

The machine may have any suitable framework provided with a longitudinally movable ram and a transversely movable rod-clamping member.

In the drawings the reference numeral 20 designates the frame of the machine, and 21 the ram movable rectilinearly in a guideway 22 arranged in the frame. The ram is operated in any suitable manner and by any approved means so as to reciprocate within the guideway 22, and in the representative form shown comprises three connected center members 23, 24 and 25 arranged in contact one above the other, flanked by two 105 110

side members 26, 27, the side members and the superposed center members 23, 24 and 25 being connected together in any approved manner so that they, in effect, are a unitary structure. The 5 ram occupies the full width of the guideway and is guided by the side walls 28, 29 thereof, and by the bottom wall 30.

Secured to the central members 23, 24 and 25 are "head-fashioning members" or forming or 10 die members 31, 32 and 33, respectively, each such member, in most instances, being cylindrical in shape and having a reduced inner end or shank 34 entered in its corresponding central member and fastened therein by a set screw 35, or otherwise. Part or all of these forming or die members, will, in some cases, be formed non-cylindrical, depending on the cross sectional formation the head of the article is to be when finished. Each shank is fastened in place by a screw rod 20 36 entered into the die member from the rear and threaded axially into the shank, as shown, said screw rod serving to retain the forming or die members in position with their shoulders 37 in firm contact against the front face of the ram, 25 and more particularly the central members thereof.

The said forming or die members project forwardly into the guideway 22 varying distances, the upper or preliminary forming or die member 30 having a long inwardly tapered axial bore 38 opening to the front. The secondary forming or die member 32 extends forwardly from the ram a greater distance than the preliminary forming or die member 31, and it is provided with a comparatively short inwardly tapering bore 39 of greater diameter, at least along the major portion of its length, than the tapering bore 38 in the preliminary forming or die member, and like the bore in the latter, opens to the front end of said 40 secondary forming or die member.

The finishing die member 33 terminates in a vertical plane which is normally between the planes of the outer ends of the two forming or die members 31 and 32, and it is solid along its 45 outer portion, and has its outer end face at a right angle to the axis thereof. This, however, may be varied, depending on the shape or contour the end surface of the head is to be in the finished article of manufacture.

50 When the ram is moved forwardly, the forming or die members, including, of course, the finishing die member, are moved with it and during each forward movement of the ram, the three die members are brought simultaneously into action against rods inserted into the machine from the front end thereof, the preliminary forming or die member operating on a plane rod, preferably but not necessarily, heated along at least a portion of that part of the rod inserted into the 55 machine, the secondary die member operating upon the rod after having had a partly or preliminarily formed head or enlargement applied thereto by the preliminary forming or die member, and the finishing die member actuating 60 upon the rudimentarily formed head, so formed by the secondary forming or die member, said finishing die member completing the head to true 65 form in shape, diameter, and length.

70 The frame of the machine is cut away along one of its walls 28, preferably along the front of the latter, as at 49, and in this cutaway portion is fitted a guide slab 41, the inner face of which is grooved, as at 42, to receive a slide bar 43 held in said groove by retainer bars 44 fastened to the 75 inner side of the guide slab 41 and overlying

the marginal portions of the slide bar 43, the front end of which is rounded, as at 45, for a purpose to appear hereinafter. The rear end of said slide bar is laterally enlarged, as at 46, and provided with a stop 47 at its inner end against which the ram 21 is adapted to strike and cause forward movement of the slide bar 43, which is cushioned in its movement in a manner to appear hereinafter. The stop 47 determines the exact extreme forward position of the ram and consequently the corresponding positions of the forming and finishing die members.

80 At its front end the guide slab 41 is beveled, as at 48, Figs. 5 and 11, and abutting against this beveled portion is the outer beveled edge 49 of the support or carrier 50 for the rod-supporting member, said support or carrier being arranged transversely in a recess 51 formed in the frame of the machine and being removable from said recess from the top of the machine, as clearly shown in Fig. 1.

85 The support or carrier 50 is provided with an opening 52 therethrough which extends from a point near the lower end thereof to the upper edge thereof, and it also has a horizontal opening 53 90 extending laterally from the opening 52.

95 The opening 53 terminates in a slot 54 into which the front end of the slide bar 43 extends and in which it is positioned for slight movement. The upper and lower walls of the opening 53 are 100 notched, as at 55, 56, respectively, and in these notches, studs 57 extending from the upper and lower faces of an actuator 58 are positioned, said actuator 58 being positioned within the opening 52 and the studs 57 being disposed centrally between the ends of the actuator and serving as pivots on which the actuator is centered for swinging movement. The actuator is disposed at a right angle to the slide bar 43 and has one end provided with a rearwardly-facing rounded projection 59, which bears against the rounded front end of the slide bar 43, and the rear face of said actuator is grooved at its other end, as at 60, the groove being concaved for engagement with another element of the machine, to be more particularly described hereinafter.

105 The support or carrier 50 is fastened to the guide slab 41 in any approved manner, and also to the frame 20 of the machine, and for this purpose has bolt holes 61 therein through which bolts 62 are passed, said bolts extending through the frame of the machine forward of the support or carrier 50, passing through the bolt holes 61, one bolt entering member 63 of a pair of rod clamping members 63, 64, terminating within the support or carrier 50.

110 In the frame of the machine is a transverse guide opening 65, and in this opening is transversely slidable a ram 66 to which the rod clamping member 64 is secured. The rod clamping member 63 has a fixed position within the machine, and it also serves as a guide wall for the slide bar 43, as clearly shown in Fig. 5. The rod clamping member 64 is therefore movable transversely within the front end of the guideway 22 and is adapted to be brought into contact with the fixed rod clamping member 63, the opposing surfaces of these rod clamping members having semi-cylindrical grooves or cavities 67, 68 and 69, which, when the rod clamping members are brought together form cylindrical openings 70, 71, 72, respectively, as clearly shown in Fig. 5. The axes of these cylindrical openings are coincident with the axes of the die members 31, 32 and 33.

Each of the semi-cylindrical grooves or cavities 67 has an inner or rear portion 73 which is of a size to correspond with that of the rod to be upset, and it also has an enlarged outer or front 5 portion 74.

Each of the semi-cylindrical grooves or cavities 68 has an enlarged inner or rear portion 75 and a smaller forward or outer portion 76, the latter being of a diameter corresponding to that of the 10 rod operated upon; the large inner or rear portion 75 being of a diameter to receive the forming or die member 32. By enlarging the rear or inner portion of each of the grooves or cavities 68, rearwardly or inwardly-facing shoulders 77 are 15 formed in the groove or cavity.

Each of the semi-cylindrical grooves or cavities 69 has a forward or outer portion 78, which is of a diameter corresponding to that of the rod to be operated upon, and a larger inner or rear 20 portion 79 forming rearwardly or inwardly-facing shoulders 80 in the grooves or cavities. The rear portions 79 of the grooves or cavities correspond in size with the finishing die 33, which they are 25 adapted to receive.

Set into each of the rod-clamping members 63 and 64 is a nicking or marking element 81 in the form of a flat comparatively thin steel slab set 30 into recesses 82 formed in the rod-clamping members and opening to the opposing faces thereof, said nicking or marking elements being held 35 within said rod-clamping members by means of screws 83 threaded into registering semi-cylindrical screw threaded grooves formed in said elements and the walls of the recesses into which 40 said elements are inserted. The inner edges of these nicking or marking elements conform to the opposing grooved surfaces of the rod-clamping members and each edge is therefore provided with a semi-cylindrical notch 84, the wall of which has 45 a V-shaped rib 85 extending outwardly therefrom to form a cutting or nicking edge.

The straight portion 86 of the inner edge of each of these nicking or marking elements is flush with the inner face of the rod-clamping 50 member in which the element is inserted, and the semi-cylindrical notch has its wall flush with the wall of the small portion of the semi-cylindrical groove 67. The smaller portion of the 55 semi-cylindrical grooves 67, 68 and 69 are adapted to clamp the rods operated upon and hold them securely against lengthwise movement during the upsetting and finishing steps applied to the rods.

The inner surface of the support or carrier 50 is recessed, as at 87, and in this recess, which 60 extends from the bottom the top of the support or carrier 50, is a rod-supporting member 88, the construction of which is clearly shown in Figs. 14 and 15. One vertical or upright edge of this rod-supporting member is straight lined, and its 65 upper and lower edges are positioned flush with the upper and lower edges of the support or carrier 50. The other vertical or upright edge of said rod-supporting member is of irregular formation, as it is notched, as at 89, 90 and 91 to 70 provide horizontal ledges or shelves, the notch 91 being offset with respect to the notches 89 and 90, which latter two are vertically aligned. Arranged in horizontal alinement with the notch 91 is a plunger or stud opening 92 which is also 75 in vertical alinement with the inner ends of the notches 89 and 90, both of which latter are rounded at their inner ends to approximate the cylindrical formation of the rods to be operated upon. When rods of other cross-sectional for- 80 mation are being upset, the rod-supporting mem-

ber may have its notches correspondingly formed. This rod-supporting member 88 is fastened to the support or carrier 50 by means of screws or bolts 93 passed through said support or carrier and entering threaded openings 94 in the rod-supporting member. The notches 89, 90 and the rod-opening 92 are, respectively, alined with the semi-cylindrical grooves 67, 68 and 69 in the opposing faces of the rod-clamping members 63 and 64 and their axes; and therefore, considering only the rounded inner ends of the notches 89 and 90, they are coincident with the rod openings formed by said semi-cylindrical grooves when the two rod-clamping members are brought together. 85

The rod-supporting member 88 is provided with a recess 95 in its inner face extending along the irregular vertical or upright edge of said member, and in this recess is fastened a shearing member 96, the outer edge of which conforms to the edge of the rod-supporting member along the region of said recess. This shearing member, therefore, also has a notch 97 extending inwardly from its outer edge which registers with the notch 91 in the rod-supporting member. It 90 further has a plunger or stud opening 98 which is in registration with the plunger or stud opening 92 in the rod-supporting member 88, and it is fastened to said member by bolts 99 passed through bolt holes 100, said bolts being threaded 105 into screw-threaded openings 101 in said shearing member.

The plunger opening 98 in the shearing member is slightly smaller than the plunger opening 92 in the rod-supporting member, but their axes 110 are coincident, and in these openings is arranged a short squaring plunger or stud 102 provided with a head 103 having a convex outer surface conforming to and adapted to bear against the concaved inner wall of the groove 60 in the pivoted actuator 58. This plunger is reduced in diameter at its inner end to conform to the diameter of the plunger opening 98 in the shearing member 96, thus providing an inwardly-facing shoulder 104 which serves to limit the inward 115 movement of said plunger or stop.

Surrounding the enlarged portion of said plunger or stud 102 so as to fit into the plunger opening 92 in the supporting member and bear at one end against the outer surface of the shearing member and at its other end against the head of said plunger is a helical spring 105 which serves to retain the plunger in its outermost position and cause the pivoted actuator 58 to swing on the short studs 57. This spring, through the 120 medium of the plunger or stud 102 and the actuator 58, also cushions the movement of the slide bar 43. A definite stop is provided for the outward movement of the outer end of the pivoted actuator, or the inward movement of the 125 inner end of said actuator, and this stop is in the form of an adjustable bolt 106 threaded into a bracket 107 secured to the bed 108 of the machine frame 20. The stud 102 and actuating parts associated therewith form what I term 130 "end-finishing means".

It may here be stated that medially the pivoted actuator is transversely enlarged and the outer and inner edges thereof rounded, and these edges bear, respectively, against the inner face 135 of the machine frame and the inner wall 109 of a notch 110 formed in the outer face of the rod-supporting member 88. The inner face of the portion of the machine frame 20, which covers 140 a portion of the support or carrier and the inner 145

portion of the pivoted actuator, has a hardened insert 111 set into it against which the rounded outer edge at the widened medial portion of the pivoted actuator bears.

5 As shown in Fig. 8, a rod, having at least a portion of its length well heated, is inserted into the machine through the notch 89 of the rod-supporting member and entered in the semi-circular groove 67 of the fixed rod-clamping member 63, the rod being so positioned that it extends rearwardly beyond said fixed rod-clamping member to a predetermined point, depending on the amount of metal in the rod to be operated upon to form the enlargement or head designed 15 for the same; the exact degree of extension of the rod beyond said fixed clamping member being shown in dotted lines in Fig. 8 and being determined in any suitable manner.

By suitable means provided in the machine (not shown), the movable rod-clamping member 64 is brought in contact with the fixed rod-clamping member 63 through the actuation of the transversely movable ram 66, and thus the rod is firmly clamped between the two clamping members against movement lengthwise, and at the same time the nickers or markers 81 nick or mark the rod at the point where it is finally to be completely severed. The longitudinally movable ram 21 is then actuated by any suitable 20 means, such as a machine of this general type is provided with, and by reason of the die members 31, 32 and 33 being secured to said ram, they are carried forwardly, with the result that the uppermost forming or die member 31 receives the projecting end of the rod, which normally is somewhat longer than the axial bore in said forming or die member, and said projecting portion is condensed lengthwise and expanded radially so that it will assume the exact shape of 25 the bore 38, as clearly shown in Fig. 8; or in other words, so that a long tapered preliminarily formed head is provided on the rod. In most instances it may be found desirable to heat the portion of the rod to be upset prior to placing the rod in the machine. After this preliminary operation, the ram 21 is moved rearwardly and the ram 66 outwardly so as to enable the rod to be lowered into the next notch 90 in the rod-supporting member and into the semi-cylindrical groove 68 in the fixed rod-clamping member. At 30 the same time the operator will insert a cold or a heated rod into the uppermost groove 67 of the fixed rod-clamping member to be operated upon to form the long tapered head, in the manner already described. The rod previously acted upon and having the long tapered head formed thereon will have the inner end of said head bearing against the shoulder 77 in the semi-cylindrical groove 68 of the fixed clamping member. With the rods thus positioned, the transversely movable ram is again moved inwardly to clamp both rods, after which the ram 21 is moved forwardly and the forming or die member 31 will act upon the rod held between the uppermost 35 grooves 67, while the forming or die member 32 will enter the enlarged portions of the semi-cylindrical grooves 68 and act upon the long tapered preliminarily-formed head positioned within said grooves. The inwardly-tapering bore 39 in said forming or die member 32 being somewhat larger in diameter and shorter than the preliminarily formed tapered head results in the metal in said head being condensed in the length of the head and radially enlarged so that the head on the rod 40 will be rudimentarily formed to the exact shape

of the inwardly-tapering bore 39, as clearly shown in Fig. 9. After both rods are operated upon they are lowered, the rod having the preliminarily formed head being lowered to the second notch in the rod-supporting member while the rod having the rudimentarily formed head thereon is lowered into the notch 91 of said rod-supporting member. This leaves the uppermost notch 89 in the rod-supporting member and the uppermost semi-cylindrical groove 67 in the fixed rod-clamping member vacant to receive a rod which has not previously been operated upon. The rods positioned uppermost and intermediate are acted upon in the manner already described, while the lowermost rod having the rudimentarily-formed head thereon will be positioned with the inner end of said head against the shoulder 80 in said groove. During the operation of bringing the rod-clamping members together, the lowermost rod will become severed where it had been previously marked or nicked, this being due to the fact that the shearing member 96 will contact with the movable rod-clamping member, which latter will move past the notched shearing edge of the shearing member and cut the rod to the length desired for the finished article. After severing the rod, the part extending outwardly from the machine is returned to a furnace or other heating apparatus, to be re-heated and operated upon, as already described. 45

When the rod clamping members are brought together after shearing the lowermost rod, the rudimentarily formed head will be positioned against the shoulders 80 in the two die clamping members, and the finishing or die member 33 will be entered in the enlarged portion of the opening 72 between said rod-clamping members formed by the grooves 69, with the result that the head will be condensed in length and expanded or enlarged radially to true cylindrical 50 form, as clearly shown in Fig. 11; or to any other form which said opening may have.

During the act of finishing the head, the pivoted actuator 58 will be operated, due to the fact that the slide bar 43 will be forced forwardly by the ram 25, said ram engaging the stock 47 secured to the rear end of said slide. This results in the pivoted actuator forcing the stud or plunger 102 inwardly against the end of the sheared-off portion of the rod retained between the clamping members, and as the stud or plunger is of a size to snugly enter the opening in the clamping members formed by the cavities 69, it will form an even end face without the usual projecting fin at one corner and beveled or rounded corner directly opposite; it will also act to square the outer end of the headed article and finish the same to true form. 55

It is also to be noted that by reason of the use of the spring 105 around the stud or plunger 102, the action of all parts is cushioned. The said spring also serves to return the pivoted actuator and the slide bar with its stop 47 to normal position.

Where, in the claims, the term "to square the end of the severed article" is employed, I mean, to form the end face of the article at a true right-angle to the axis of the same.

Having thus described my invention, what I claim is:

1. A machine for upsetting rods to form heads thereon, comprising means for forming a head on a rod, means to sever the rod to form a headed article of the desired length, and means to square the severed end of the article to provide 60

- an even end face for the same at a true right angle to the axis of the article. 80
2. A machine for upsetting rods to form heads thereon, comprising means for forming a head on a rod, means to sever the rod to form a headed article of the desired length, and end-finishing means to exert pressure against the severed end of the article brought into action by the means employed for forming the head on said rod, said end-finishing means forming an even end face for the article without an overhanging fin or a beveled or rounded corner. 85
3. A machine for upsetting rods to form heads thereon, comprising a ram, forming elements secured to the ram to form a head on a rod, a pivoted actuator, means for severing the rod at the desired distance from the head, and a plunger actuated by said pivoted actuator forced against the severed end of the article to finish the same true and at right angles to the axis of the rod. 90
4. In a machine for upsetting rods to form heads thereon, means for clamping a rod, means to form a head on the inner end of said rod, shearing mechanism for severing the rod to form a headed article, and means brought into action by said head-forming means acting against the severed end of the headed article to finish said severed end to true form and at an angle to the axis of the rod. 95
5. In a machine for upsetting rods to form heads thereon, means for clamping a rod, means to form a head on the inner end of said rod, shearing mechanism for severing the rod to form a headed article, and means acting against the severed end of the headed article and adapted to slightly enter said clamping means to finish the severed end of the headed article to true form and at an angle to the axis thereof, said clamping means determining the true diameter of said severed end under action of said last-mentioned means. 100
6. In a machine for upsetting rods to form heads thereon, clamping members relatively movable to clamp a rod therebetween, shearing mechanism adjacent said clamping members to shear a rod to predetermined length, said shearing mechanism including a shearing blade having an opening therethrough, a rod supporting member to which said shearing blade is secured provided with an opening co-axial with the opening in said shearing blade and of larger diameter, a plunger within said openings having a head thereon, a spring surrounding said plunger and bearing at one end against said head and at its other end against said shearing blade, a pivoted member normally bearing against said plunger, and means for actuating said pivoted member to actuate said plunger when the rod is clamped between said clamping members and otherwise operated upon. 105
7. In a machine for upsetting rods to form heads thereon, clamping members relatively movable to clamp a rod therebetween, a forming element adapted to act upon the inner end of a rod clamped between said clamping members, a ram to which said forming element is secured movable toward said clamping members to bring said forming element into action against the inner end of said rod, movable means extending from a point within the path of said ram forwardly to and around the front end of said clamping members including a stud adapted to act against the front end of said rod to complete the same to finished form. 110
8. In a machine for upsetting rods to form enlargements thereon, clamping members relatively movable to clamp a rod therebetween so as to have free end portions, means for shearing said rod upon clamping the same so that the outer end of the rod clamped will have at least a portion thereof flush with the outer ends of said clamping members, a forming element adapted to act upon the inner end of said rod, a ram to which said forming element is secured movable toward said clamping members to bring said forming element into action against the inner end of said rod, a stud maintained normally in line with said rod at the outer end thereof, and means actuated by said ram to operate said stud and force the same against the outer end of said rod and between said clamping members. 115
9. A machine for upsetting rods to form enlargements thereon, comprising clamping members having registering grooves adapted to receive and clamp a rod along a region between its ends when said clamping members are brought together so that free portions of the rod are provided at the inner and outer ends of the clamped region, a movable element normally spaced from the inner ends of said clamping members movable toward the same, a forming element secured to said movable element adapted to act upon the inner free end of said rod when clamped between said clamping members, means to sever said rod at the front end of its clamped region in line with the outer ends of said clamping members, and means to square the outer end of said rod while said forming element passes through at least a portion of its movement, said means being actuated by said movable element. 120
10. A machine for upsetting rods to form heads thereon, comprising a frame, a clamping member arranged in fixed relation within said frame, a clamping member movable toward and from said first-mentioned clamping member to clamp a rod between the two along a region between its ends to expose free portions of the rod at its inner end and outwardly from the clamped region thereof, a ram normally spaced from the inner ends of said clamping members and movable toward the same, a forming element carried by said ram and adapted to act upon the inner end of said rod, a slide bar disposed between said fixed clamping member and said frame and having a portion extending into the space between said ram and said clamping members, a pivoted actuator disposed at right angles to said slide bar and engaged at one end by the latter, said actuator being pivotally mounted between its ends, means for shearing the rod in line with the front ends of said clamping members, a stud spring-pressed outwardly away from the sheared end of said rod and maintained against the other end of said actuator, said slide bar being adapted to be actuated by said ram during the final portion of its outward movement and cause actuation of said actuator to force said stud against the sheared end of said rod to square the same between said clamping members in close proximity to the outer ends of the latter. 125
11. A machine for upsetting rods to form enlargements thereon, comprising means to clamp a rod with free portions at its inner end and outwardly from said means, movable means to engage the free inner end of said rod to form the same to desired shape, means for shearing said rod at the outer end of said clamping means, an element conforming to the cross sec- 130
12. A machine for upsetting rods to form enlargements thereon, comprising means to clamp a rod with free portions at its inner end and outwardly from said means, movable means to engage the free inner end of said rod to form the same to desired shape, means for shearing said rod at the outer end of said clamping means, an element conforming to the cross sec- 135
13. A machine for upsetting rods to form enlargements thereon, comprising means to clamp a rod with free portions at its inner end and outwardly from said means, movable means to engage the free inner end of said rod to form the same to desired shape, means for shearing said rod at the outer end of said clamping means, an element conforming to the cross sec- 140
14. A machine for upsetting rods to form enlargements thereon, comprising means to clamp a rod with free portions at its inner end and outwardly from said means, movable means to engage the free inner end of said rod to form the same to desired shape, means for shearing said rod at the outer end of said clamping means, an element conforming to the cross sec- 145
15. A machine for upsetting rods to form enlargements thereon, comprising means to clamp a rod with free portions at its inner end and outwardly from said means, movable means to engage the free inner end of said rod to form the same to desired shape, means for shearing said rod at the outer end of said clamping means, an element conforming to the cross sec- 150

tional formation and transverse dimension of said rod normally positioned in slightly spaced relation to the sheared end of said rod, and means actuated during the formation of the 105 inner end of said rod for actuating said element.

12. In a machine for upsetting rods to form heads thereon, clamping members relatively movable and provided with depressions in opposed faces to receive and clamp a rod with its 110 inner end free to be operated upon, the outer end of said rod being in line with or slightly within said depressions, means adapted to enter said depressions at the outer ends of said clamping members to square the outer end of said rod within said depressions, and means for actuating 115 said last-mentioned means from a movable part of said machine.

13. In a machine for upsetting rods to form enlargements thereon, two clamping members 20 relatively movable to clamp a rod therebetween, means for shearing the rod at the front end of said clamping members, a stud normally slightly spaced from the outer ends of said clamping members and so spring retained, a support for 25 said stud, an actuator pivoted between its ends within said support and disposed at an angle to said stud, one end of said actuator having the outer end of said stud bearing thereagainst, and means for actuating said actuator from the 30 opposite end thereof.

14. A machine for upsetting rods to form heads thereon, comprising a ram, forming ele- 35

ments secured to the ram to form a head on a rod, means for severing the rod at the desired distance from the head to form a headed article, an actuator, and a plunger actuated by said actuator and forced against the severed end 80 of the article to finish the severed end face thereof smooth and even without a fin or a beveled or rounded corner.

15. A machine for upsetting rods to form heads thereon, comprising means to clamp a rod, means to exert pressure against one end thereof to form the head thereon, a plunger to engage the opposite end of the rod while retained in said clamping means, and means to exert pressure against 85 said plunger to provide a smooth end face for said last-mentioned end of the rod without a projecting fin or a beveled or rounded corner. 90

16. A machine for upsetting rods to form heads thereon, comprising means to clamp a rod, forming elements to form a head on one 95 end of said rod while clamped within said clamping means, means for severing the rod at the desired distance from the head to form a headed article, a plunger adapted to engage the severed end of said headed article and compress 100 the same at the severed end slightly within said clamping means, and means for actuating said plunger to finish the severed end of the article to true form and to assure exact length of the 105 finished article.
